UNITED STATES PATENT OFFICE.

WILLIAM WOOD WILSON, OF BOSTON, MASSACHUSETTS.

CENTERING-FORM FOR CONCRETE CONSTRUCTION.

1,118,168.

Specification of Letters Patent.

Patented Nov. 24, 1914.

Application filed October 19, 1910. Serial No. 587,858.

To all whom it may concern:

Be it known that I, WILLIAM W. WILSON, a citizen of the United States, and residing in Boston, county of Suffolk, State of Massachusetts, (whose post-office address is 15 Exchange street, Boston, Massachusetts,) have invented an Improvement in Centering-Forms for Concrete Construction, of which the following description, in connection with the accompanying drawings, is a specification, like letters on the drawings representing like parts.

This invention relates to centering forms for concrete construction.

15 The invention will be best understood by reference to the following description when taken in connection with the accompanying illustration of one specific embodiment thereof, while its scope will be more particularly pointed out in the appended claims.

20 In the drawings: Figure 1 is a plan view of a floor slab embodying certain features of the invention; Fig. 2 is a section in elevation on the line 2—2 in Fig. 1, showing the metal forms removed, but the wooden forms still in position; Fig. 3 is an enlarged sectional elevation showing both the wood and metal forms in place; Fig. 4 is a plan view of one of the metal panel forms; and Fig. 5 is a detail in sectional elevation showing the variation in depth in the intermediate beams which can be obtained through the use of the illustrated 25 metal form.

30 Referring to the drawings, I have there shown in Figs. 1 and 2 a monolithic floor and ceiling construction having certain advantageous features not only in itself but also the facility with which it can be molded. The floor slab shown is supported between the main girders 1, one of which is arranged on each side of the slab, the girders at their intersections being supported upon the molded or other columns 2. The floor portion 3 which is preferably 35 molded simultaneously with the girders 1 has its underside subdivided into panels 4 and has formed thereon relatively smaller 40 intersecting beams 5 which extend between opposite girders and border upon and define or form the said panels. Because of this construction the floor slab is so stiffened by the small beams that the same strength 45 can be obtained from a lesser amount of

concrete and from a lesser depth of beam and girder than in the constructions heretofore prevailing, leaving a material gain in the clearance space from the floor below to the ceiling above. Such a ceiling can be readily formed by means of the removable metal molds, hereinafter described, such molds having however features of advantage which render them useful and advantageous in molding operations other than those connected with the specific form of ceiling construction described.

50 In molding the above-described ceiling each panel thereof is preferably formed by means of a removable metal form, the latter being closed at the top by the piece 6, herein rectangular and square in shape, such top being provided with the inclined side walls 7 extending continuously around said top piece.

55 A great fault of many metal forms heretofore used for molding concrete has been either their extreme weight, or, when formed of thin sheet metal, a lack of stiffness and a tendency to distort after a short 60 usage. The continuous side walls of the disclosed form, however, impart thereto a stiffness and rigidity which obviates this difficulty, while permitting its construction out of relatively light material.

65 In order to stiffen the flat top of the form, while leaving a smooth sheet metal forming face or surface thereto, there is herein provided for such top piece stiffening means on the inside face thereof, said stiffening means 70 comprising one or more rib-like members 8, preferably in the form of a light T-iron.

75 Adjacent panel forms are so arranged with their inclined sides converging in proximity to each other that such sides form 80 the beams 5; the bottom of the beams being formed by means such as the wooden strip or other member 9 bridging the space between the sides of adjacent forms. Such strip is supported in any suitable way, as 85 upon the temporary posts 10 arranged one at each beam intersection. At each post and on each side thereof there is provided a block 11 to which and to the post there are secured the strips or other supporting members 12 which extend longitudinally below the beams at sufficient height so that they serve as rests or supports for the lower edges of the metal panel forms, the latter 90 being provided each with an inturned flange 110

13 which not only adds to the rigidity of the form, but gives a stable support thereto on the strips 12. If desired, the forms may be additionally secured to the strips 12 by any 5 suitable means such as spikes, one of which is shown in dotted lines in Fig. 3.

With the panel forms and the bridging members 9 arranged in the manner described 10 the concrete may be poured and allowed to harden and the metal forms removed in about two days, leaving the structure in the condition shown in Fig. 2, thereby rendering the forms available for other molding operations while the ceiling is finally setting. 15 This mode of supporting the panel forms not only permits their ready removal without disturbance of the beam positioning forms 9, but it is possible to vary the depth or width of the molded beam while still using 20 the same identical metal form. This possibility is illustrated by Fig. 5. If it is desired to mold the beam 5 of greater depth, a shorter temporary post 14 is utilized so that the bridging member 9, which is correspondingly reduced as to width, touches 25 the sides of the adjacent panel forms nearer their edges. If it is desired to lessen the depth of the beam 5, posts are selected of greater length, so that the mold bottom 30 member 9 approaches nearer the top of the form in some such fashion as is shown in dotted lines in Fig. 5. The width of the beam can be varied by separating the forms more or less and interposing a wider or narrower 35 lower bridging piece as the case may be.

In order conveniently to handle or transport the metal forms, there is preferably provided a small perforation 15 in the top of each, which may be normally closed by 40 the pivoted closure 16. The closure may be swung back and a hook or other implement inserted through the perforation conveniently to lift the form.

While I have herein shown and described 45 for purposes of illustration one specific form of the invention it is to be understood that the same is not limited to the details or relative arrangement of the parts herein set forth, but that various modifications may be

made without departing from the spirit of 50 the invention.

Claims:

1. A removable metallic centering form for concrete construction comprising a single member having a rigid bottom provided with a marginal web forming a continuous side wall upon all sides of said bottom, said web being provided with an in-turned flange forming a continuous stiffening means bounding on all sides the space 55 within said form.

2. A removable metallic centering form for concrete construction comprising a single member having a rigid bottom provided with a marginal web forming continuous side walls 65 upon all sides of and converging toward said bottom, said web being provided with an in-turned flange forming a continuous stiffening means bounding on all sides the space within said form.

3. A removable metallic centering form for concrete construction comprising a single member having a bottom provided with a marginal web forming a continuous side wall upon all sides of said bottom, said 75 web being provided with an in-turned flange forming a continuous stiffening means bounding on all sides the space within said form, and means for stiffening the inner face of said bottom.

4. A removable metallic centering form for concrete construction comprising a single member having a bottom provided with a marginal web forming a continuous side wall 85 upon all sides of said bottom, said web being provided with an in-turned flange forming a continuous stiffening means bounding on all sides the space within said form, and a rib-like stiffening member on the inner face of said bottom.

In testimony whereof, I have signed my name to this specification, in the presence of two subscribing witnesses.

WILLIAM WOOD WILSON.
